UNITED STATES PATENT OFFICE.

WILLIAM H. WELSH, OF COLLINGSWOOD, NEW JERSEY.

MOLDING-CASE FOR USE IN ELECTROTYPEING AND PROCESS OF MANUFACTURING SAME.

SPECIFICATION forming part of Letters Patent No. 752,493, dated February 16, 1904.

Application filed October 18, 1903. Serial No. 176,900. (No model.)

To all whom it may concern:

Be it known that I, WILLIAM H. WELSH, a citizen of the United States, residing at Collingswood, in the county of Camden and State 5 of New Jersey, have invented new and useful Improvements in Molding-Cases for use in Electrotypeing and Processes of Manufacturing the Same, of which the following is a specification.

10 This invention relates to certain new and useful improvements in molding-cases for use in electrotypeing and process of manufacturing the same.

15 The object of the invention is to prepare the molding-case in such a manner so as to prevent the sticking of the impressionable composition of the case to the cut, half-tone, or form while making the impression.

20 A further object of the invention is to prepare the molding-case in such a manner so as to prevent the slipping or spreading of the impressionable composition of the case while the impression is being made from the cut, half-tone, or form.

25 The foregoing objects are obtained by coating or powdering the impressionable composition of the case with an impalpable powdery substance free from grit and other substances injurious to the impression and which I term 30 "flour of copper," and after the coating of the impressionable composition with the flour of copper the case is finished in the known manner.

35 The impalpable powder or flour of copper used in connection with the process, to be hereinafter more fully set forth, is obtained from rendering by grinding or in any other suitable manner the siftings of electrodeposited copper powder impalpable.

40 To more fully set forth the new and improved molding-case for use in electrotypeing and the manner in which it is manufactured for obtaining the objects hereinbefore set forth, reference is had to the following description and 45 accompanying drawing.

In the drawing, which illustrates a perspective view of a molding-case prepared in accordance with my invention, 1 denotes the ordinary backing of the case, 2 the impressionable composition mounted thereon, which may

be of wax or any other suitable material, and 3 the coating of flour of copper.

The wax or other composition in which the impression is made is cast upon a rectangular or other suitably-shaped backing, so that the 55 impressionable material when cast will be of substantially the same contour as the backing. The impressionable material is then allowed to solidify to the point desired, and the upper surface thereof is then shaved or otherwise 60 acted upon so as to form it even and smooth throughout. The copper powder or flour of copper prepared as set forth is then evenly distributed throughout the smooth and even surface of the impressionable material by any 65 suitable means, preferably by a brush. After the case has been prepared in the foregoing manner it is then passed through the ordinary steps of electrotypeing—that is to say, the impression is made, subjected to the black-lead- 70 ing machine to be coated with graphite or plumbago, and then to the electrolytic bath.

I have discovered that the flour of copper referred to, and which is obtained from electrolytically-deposited copper powder in the 75 manner as hereinbefore set forth, being practically free from impurities possesses a non-slipping quality, and consequently after the impressionable material has been powdered with this flour of copper the composition will 80 not stick or adhere to the cut, half-tone, or form when making an impression. Furthermore, I have found that this flour of copper will also prevent the composition, or rather the impressionable material, from spreading 85 when an impression is made, and by the employment of the powder or flour of copper made as set forth the objection to the ordinary bronze powder of commerce is overcome, as it is a well-known fact to electrotypers that when 90 the ordinary copper powder of commerce is employed it often slips, breaking the lines of the impression off, necessitating partly filling up of the lines or dots with molding-lead, and when the lines are in such condition the cuts 95 or half-tones are not clear and sharp as they would be if molded clean with the powdery substance which I have termed "flour of copper;" nor can the electrodeposited copper powder be used, for the reason that it is too 100

gritty, and consequently it would be injurious to the case, which is evident, owing to its gritty nature. Therefore it is necessary that such copper powder should be sifted and the 5 siftings be rendered impalpable to form what I have termed "flour of copper," which possesses the following characteristics: that it is not gritty, will not slip, and will prevent when used in the manner as hereinbefore set forth 10 the sticking, slipping, or spreading of the impressionable composition of the case while the impression is being made from the half-tone, cut, or form.

Having thus fully described my invention, 15 what I claim as new, and desire to secure by Letters Patent, is—

1. A process for manufacturing molding-cases for use in electrotyping, consisting of casting an impressionable composition, coating 20 the said composition with flour of copper, forming an impression in the said composition, subjecting the impressed composition to a black-leading machine, and then subjecting it to an electrolytic bath.

2. A process for manufacturing molding-²⁵ cases for use in electrotyping, consisting of casting an impressionable composition, suitably evening the upper surface of said composition, coating the said composition with flour of copper, forming an impression in the said ³⁰ composition, subjecting the impressed composition to a black-leading machine, and then subjecting it to an electrolytic bath.

3. As a new article of manufacture, a molding-case for use in electrotyping obtained by ³⁵ casting an impressionable composition, coating the said composition with flour of copper, forming an impression in said composition, then subjecting it to a black-leading machine, and then to an electrolytic bath. ⁴⁰

In testimony whereof I have hereunto set my hand in presence of two subscribing witnesses.

WILLIAM H. WELSH.
